WIRe CUTTER

August A. Westman, Carnation, Wash.

Application December 13, 1943, Serial No. 514,188

2 Claims. (Cl. 30—190)

This invention relates to a wire cutter and, more particularly, to a wire cutting tool having a compound leverage mechanism for improving the closing action of opposed jaws.

It is an important object of my invention to provide a wire cutter that is powerful without requiring great manual strength to operate the same.

Another object of my invention is the provision, in a wire cutter, of a toggle joint which will compound the leverage action applicable to a pair of opposed jaws without unduly complicating the tool over conventional cutters and which can be simply and easily formed and assembled.

A still further and more specific object of my invention is to provide, in a tool of the type described, a simple and efficient spring means for opening the jaws without interfering with the operation of the tool or unduly complicating its construction.

The foregoing objects and others ancillary thereto I prefer to accomplish as follows:

According to a preferred embodiment of my invention, I dispose upon a handle a jaw rigid therewith and also a pivot adjacent the heel of said jaw. In certain instances the jaw may have a cutting edge. Mounted to swing about said pivot is a second jaw which includes a rigid angularly disposed lever portion extending from said pivot in a manner that said jaw and said lever comprise a bell crank. Pivottally attached to said lever is a second handle which lies alongside said first handle. Between said first handle remote from the jaw pivoted thereon, and said second handle relatively adjacent its pivotal connection with the lever portion of the movable jaw, is a rigid link operable during closing of the two handles together to swing the bell crank jaw about its pivotal connection with the first handle. Said rigid link and that portion of the second handle between the connection of the link with the handle and the handle with the lever comprises a toggle joint, the links of which are to be brought into substantial alignment when the two handles are closed together. Under certain circumstances the rigid link may be extended or contracted for the purposes of adjusting the two jaws to obtain proper closure. Between said second handle and said rigid link is a spring, here shown to be a bow spring, which tends to urge said handles apart and to open the jaws from their closed position. Means movable between said first handle and the lever on said movable jaw, adapted to be swung into a position for en-

gagement with a stud or other fixture, retains said jaws in closed relation to each other and against the urging of the opening spring.

The novel features that I consider characteristic of my invention are set forth with particularity in the appended claims. The invention itself, however, both as to its organization and its method of operation, together with additional objects and advantages thereof will best be understood from the following description of a specific embodiment when read in connection with the accompanying drawing, in which:

Figure 1 is the view in side elevation of my wire cutting tool with portions broken away for the convenience of illustration; and

Figure 2 is a fragmentary view in side elevation of the opposite side of the tool from that shown in Figure 1 and showing the tool in closed position with the jaws locked together.

A wire cutting tool must have at least two totally distinct characteristics; it must be capable of severing a multitude of sizes and hardnesses of wire with ease to the operator; and it must be capable of construction so as to receive a strong closing force in the compounding of power for the cutting operation without placing undue strains and stresses upon the various working parts. Accordingly, a preferred embodiment of my invention referring to the drawing, is constituted by a first handle 10 here shown as U-shaped in cross-section and having on its forward end a jaw 12 and pivot ears 14.

A segmental member 16 is mounted on the pin 18 supported in pivot ears 14 so that the jaw 20 may be swung toward and away from the jaw 12. A second handle 22, similarly U-shaped in cross-section as is handle 10, is pivotally coupled to the segment 16 by pin 24. Handles 10 and 22 as shown in Figure 1 lie in substantially the same place and, in use, are moved toward and away from each other usually by being hand gripped. A link 26 extends between the pin 28 mounted in handle 10 and the pin 30 mounted in handle portion 22.

It will be seen that the link 26 and that portion of handle 22 between pivots 24 and 30 constitute a toggle joint which is actuated by pressure applied upon pin 30 by the closing together of handle 10 and 22 whereby the segment 16 is swung about the axis of pin 18 to bring jaws 12 and 20 together and tend to align the links forming the toggle joint.

Link 26 is here shown as divided into two parts, 32 and 34 each of which preferably have roughened faces. One of the two parts is slotted and

the other drilled and tapped to receive screws 36 for clamping the two parts together in an adjusted relationship.

Link 26, adjacent that end pivoted to pin 30 has a notch 38 in which is seated the end of bow spring 40 that is secured to handle 22 near its outer end by the rivet or other fastener 44.

Referring specifically to Figure 2, wherein is shown a portion of the other side of the tool than which appears in Figure 1, there will be seen a latch link 46 pivotally mounted on the handle 10 by pin 48 having a notch at its opposite end for engagement on a protruding portion of the pivot pin 24. An outstanding flange 52 facilitates the manual movement of the latch link 46 into or out of a locking position.

Assuming the tool to be open as shown in Figure 1 and a wire W to be cut, the jaws of the tool are brought into engagement with wire W and the handles 10 and 22 are closed together by the operator manually. As the two jaws close together, the link 26 being immovable on handle 10, because of its pivotal connection therewith by the pin 28, causes the pin 30 to swing in an arc about pin 28 in a direction toward the jaws of the tool. This action in turn urges the pin 24 forward in an arc about the axis of the pin 18, causing the segment 16 to swing and the jaws 12 and 20 to close together. The action is that of a toggle joint and a material compounding of the power applied to the jaws 12 and 20 results. A cutting or gripping operation between these jaws is relatively easy. During such a closing operation the bow spring 40 is more greatly bowed than is shown in Figure 1 so that the power stored therein during a jaw closing operation will be available when the power is released from handles 10 and 22. Spring 40 causes the jaws to open and the handle members to be spread apart.

It is important that the jaws 12 and 20 be adjusted properly with relation to each other, and in order to accomplish this adjustment simply I divide link 26 into two portions whereby it may be elongated or shortened in the manner previously described. Such an adjustment would occasionally be necessitated by resharpening of one or both of the jaws or because of wear in the various pivots.

To close the jaws and retain them in that

closed position, all that need be done is to swing the latch link 46 from the dotted line position shown in Figure 1 to the solid line position shown in Figure 2.

5 While I have shown and described particular embodiments of my invention, it will occur to those skilled in the art that various changes and modifications may be made without departing from the invention, and I, therefore, aim in the 10 appended claims to cover all such changes and modifications as fall within the true spirit and scope of my invention.

Thus having described my invention, I claim:

1. A wire cutter, comprising: a first handle 15 having a cutting jaw, a pivot on said handle adjacent the heel of said cutting jaw, a second cutting jaw mounted in said pivot adjacent the heel of said jaw to swing into cutting relation with respect to the jaw on the first handle, a lever 20 angularly and rigidly disposed in respect to said second jaw, two links pivoted together, to form a toggle joint, one of said links being pivoted to said lever and the other of said links being pivoted to said first handle whereby the toggle joint 25 is disposed between said first handle and said lever, a handle extension on the link of said toggle joint pivoted to the lever, a bow spring between the other link of said toggle joint and said handle extension to urge breaking of said toggle 30 joint and consequent opening of the cutting jaws.

2. A wire cutter comprising: a first handle 35 having a cutting jaw, a pivot on said handle adjacent the heel of said cutting jaw, a second cutting jaw mounted in said pivot adjacent the heel of said jaw to swing into cutting relation with respect to the jaw on the first handle, a lever angularly and rigidly disposed in respect to said second jaw, two links pivoted together, to form a toggle joint, one of said links being pivoted to 40 said lever and the other of said links being pivoted to said first handle whereby the toggle joint is disposed between said first handle and said lever, said link pivoted to said first handle having a notch adjacent the intermediate pivot of the toggle joint, and a bow spring anchored to said second handle and seated in said notch to urge breaking of said toggle joint and consequent opening of the cutting jaws.

AUGUST A. WESTMAN.
